UNITED STATES PATENT OFFICE.

ARTHUR SPEAR, OF CHICAGO, ILLINOIS, ASSIGNOR TO J. P. GARDNER, OF CHICAGO, ILLINOIS.

SHUTTLE-DRIVING MECHANISM FOR SEWING-MACHINES.

SPECIFICATION forming part of Letters Patent No. 745,256, dated November 24, 1903.

Application filed August 31, 1901. Renewed April 9, 1903. Serial No. 161,922. (No model.)

To all whom it may concern:

Be it known that I, ARTHUR SPEAR, a citizen of the United States, residing at Chicago, in the county of Cook and State of Illinois, have invented certain new and useful Improvements in Shuttle-Driving Mechanism for Sewing-Machines, of which the following is a full, clear, and exact specification.

My invention relates more particularly to 10 that class of sewing-machines in which both the needle-bar and the shuttle are driven by rotary shafts connected together so that one will drive the other; and my invention has for its primary object to simplify and cheapen 15 the construction and principal of operation of a machine of this character whereby it will be feasible and better adapted for embodiment in the form of a toy machine, while at the same time it will be durable and efficient.

With these ends in view my invention consists in certain features of novelty in the construction, combination, and arrangement of parts by which the said objects and certain 25 other objects hereinafter appearing are attained, all as fully described with reference to the accompanying drawings, and more particularly pointed out in the claim.

In the said drawings, Figure 1 is a vertical 30 longitudinal sectional view of a part of a sewing-machine frame embodying my improvements; and Fig. 2 is a detail sectional view, taken on the line 2-2, Fig. 1, looking in the direction of the arrows.

1 is the base of a sewing-machine frame which in the form of the invention shown in the drawings is of the toy variety and designed to be set upon an ordinary table or any other support where it is desired to use the 35 machine, and as a consequence pulley 2, which drives shuttle-shaft 3, is mounted at a sufficient elevation from the lower edge of the base 1 to avoid touching the table or other surface upon which the machine might be supported.

The shuttle-shaft 3, which may be connected to the shuttle (not shown) in the usual or any suitable way, is provided at a point within the standard 4 of the sewing-machine frame 40 with a crank 5, and this crank is connected to a similar crank 6, formed on needle-bar

shaft 7, journaled in arm 8 of the standard. The connection between these two cranks is effected by means of a lever 9, whose ends are provided with suitable straps 10, embracing the wrists of the cranks and whose intermediate portion is provided with a sliding fulcrum. This fulcrum is constituted by a ball 11, which is formed on or secured to the lever 9 and fits accurately within a cylindrical 55 guideway or bore 12, formed vertically in a guide-block 13, cast in or secured to the standard 4.

By the described means it will be seen that assuming the parts to be in the position shown 60 in Fig. 2 and the shuttle-shaft 3 to be rotated toward the right the initial action of the lever 9 will be to swing laterally on its fulcrum 11 toward the right at the lower end and toward the left at the upper end, and 70 consequently the dead-centers will be passed, and as the upper crank passes the dead-center it will be at the same time pulled downwardly by the endwise motion of the lever, and this downward movement will continue 75 until the lower crank reaches the position diametrically opposite that shown in Fig. 2, the upper crank being at this instant also on dead-center; but inasmuch as the lower crank moves toward the left at this time the upper 80 crank will be pushed toward the right laterally beyond the dead-center before the upward thrust on the lever 9 takes place to a sufficient degree to cause the parts to lock. It is of course understood that during the described 85 movements of the cranks and lever the ball-fulcrum 11 slides up and down in its guideway 12, which constitutes a perfect bearing and guide for the ball, whose wearing-surfaces are continually changing, and hence 90 the fulcrum remains reasonably tight for a great length of time. It is also understood that the ball 11 should be of sufficient diameter to permit of the oscillation of the lever within the guideway 12, which latter is large 95 enough to permit the end of the lever to be passed through it.

The pulley 2 is driven by a crank-wheel 14, which may be journaled on a projecting end 15 of the needle-bar shaft 7 and held in place 100 by headed screw 16, wheel 14 being connected to pulley 2 by a suitable belt 17. This method

of driving the shaft 3 is resorted to in order that the lower pulley 2 may be smaller than could be the case if it were utilized as the crank-wheel, it being understood that a 5 larger wheel or pulley would necessitate a greater elevation of the shuttle-shaft 3.

Those skilled in the art to which this invention relates will of course understand that the cranks 5 6 should be of equal throw, or 10 else the fulcrum 11 should be so positioned with reference to the length of the lever 9 as to give one end of the lever a degree of oscillation equal to the crank of greater throw and the other end a degree equal to the throw 15 of the other crank. In the example shown in the drawings the cranks being of equal throw the fulcrum 11 is positioned at the mid-length of the lever, and although it is continually changing its altitude or position with 20 reference to the length of its guideway 12 the degree of oscillation never changes.

If desired, the loose pulley 14 may be provided with suitable means, such as set-screw 18, whereby it may be secured to shaft 7 should

it be found desirable to drive pulley 2 by a 25 belt from the ordinary treadle mechanism, so that wheel 14 in that event may be made to serve as a fly-wheel.

Having thus described my invention, what I claim as new therein, and desire to secure by 30 Letters Patent, is—

A shuttle-driving mechanism for sewing-machines comprising a frame constructed with a base, a standard having an arm and a fixed guide-block formed with a bore providing a guideway, a shuttle-operating shaft having a crank and journaled in the upper part of the base, a needle-bar-operating shaft having a crank and journaled in the arm of the standard, a lever having a ball-fulcrum 35 working freely in the guideway of the fixed guide-block, means whereby the lever is connected with the shafts, and a wheel mounted on one of said shafts.

ARTHUR SPEAR.
